CLAIM

I claim the ornamental design for a motorcycle pack mount, as shown and described.

DESCRIPTION

FIG. 1 is a perspective view of a motorcycle pack mount, showing my new design;

FIG. 2 is a front elevational view of the motorcycle pack mount of FIG. 1;

FIG. 3 is a rear elevational view of the motorcycle pack mount of FIG. 1;

FIG. 4 is a right side elevational view of the motorcycle pack mount of FIG. 1;

FIG. 5 is a left side elevational view of the motorcycle pack mount of FIG. 1;

FIG. 6 is a bottom plan view of the motorcycle pack mount of FIG. 1; and,

FIG. 7 is a top plan view of the motorcycle pack mount of FIG. 1.

1 Claim, 6 Drawing Sheets
